(57) **CLAIM**

The ornamental design for a candle or spherical object holder, as shown and described.

DESCRIPTION

FIG. 1 is an isometric view of a first embodiment of a candle or spherical object holder, shown in use;
FIG. 2 is a front elevation view of the first embodiment; the rear elevation view being a mirror image thereof;
FIG. 3 is a left elevation view of the first embodiment; the right elevation view being a mirror image thereof;
FIG. 4 is a top plan view of the first embodiment;
FIG. 5 is a bottom plan view of the first embodiment;
FIG. 6 is an isometric view of a second embodiment of the candle holder, shown in use;
FIG. 7 is a front elevation view of the second embodiment;
FIG. 8 is a rear elevation view of the second embodiment;
FIG. 9 is a left elevation view of the second embodiment; the right elevation view being a mirror image thereof;
FIG. 10 is a top plan view of the second embodiment; and,
FIG. 11 is a bottom plan view of the second embodiment. The broken lines shown in the drawings illustrate portions of the candle or spherical object holder that form no part of the claimed design.
